UNITED STATES PATENT OFFICE.

PHILIP RICHY CHABASSOL, OF GRADATIM, PENNSYLVANIA.

TRACK FOR BED-CASTERS.

No. 927,113.

Specification of Letters Patent.

Patented July 6, 1909.

Application filed January 2, 1909. Serial No. 470,500.

To all whom it may concern:

Be it known that I, PHILIP RICHY CHABASSOL, a citizen of the United States, residing at Gradatim, in the county of Allegheny and State of Pennsylvania, have invented certain new and useful Improvements in Tracks for Bed-Casters, of which the following is a specification, reference being had to the accompanying drawings.

This invention relates to improvements in tracks for the casters of beds or other pieces of furniture.

The object of the invention is to provide a simple and practical caster track which will enable a bed or other piece of furniture to be readily pulled away from a wall and replaced without danger of tearing the carpet and which will be so constructed that when not in use it may be folded back under the bed or the like and readily secured in such folded position and also in its extended or open position.

With the above and other objects in view, the invention consists of the novel features of construction and the combination and arrangement of parts hereinafter fully described and claimed, and illustrated in the accompanying drawings, in which—

Figure 1 is a plan view of a pair of caster tracks showing them in their extended position in full lines and in their folded position in dotted lines, the bed being indicated in dot and dash lines; Figs. 2 and 3 are detail vertical sections taken, respectively, on the planes indicated by the lines 2—2, 3—3 in Fig. 1; Fig. 4 is a detail horizontal section showing the catch for securing the movable section of the track in its folded position; and Fig. 5 is a similar view showing the hinge connection for the track sections and the catch for securing the latter in their extended position.

In the drawings B indicates a bed or other piece of furniture and C its casters which are adapted to run in the improved tracks 1 which are suitably placed upon the carpet or floor covering. Each of the tracks 1 consists of a long section 2 and a short section 3, which sections are united by hinges 4 so that the short outer sections may fold inwardly against the long or main inner sections 2, as indicated in dotted lines in Fig. 1. Each of the sections of the tracks are in the form of channeled or U-shaped troughs and the long inner or main sections 2 correspond in length to the width of the bed or piece of furniture

B. The short outer or foldable sections 3 may be of any desired length according to the distance which it is desired to move the bed away from the wall.

For the purpose of securing the sections 2, 3 of each track in extended operative position, shown in full lines in Fig. 1, a catch spring 5 is secured by screws or similar fastenings 6 to the outer side wall of the section 2 and has its free projecting end curved outwardly, as shown at 7, to provide a finger piece and formed with an aperture 8 to receive a pin or stud 9 projecting from the corresponding side wall of the section 3. It will be seen that when the latter is swung outwardly to its position shown in Fig. 1 the pin 9 will swing the curved end 7 of the spring catch outwardly until it enters the aperture or opening 8, whereupon, said section 3 will be locked in its extended or open position.

For the purpose of securing the foldable outer sections 3 in their folded position shown in dotted lines in Fig. 1, each of them has secured to its outer end an angular catch spring 10, one end of which is fastened by screws or the like 11 and the other end of which is bent to form a substantially U-shaped loop 12 with a curved extremity 13. This spring loop 12 is adapted to engage a curved head 14 formed by bending upon itself one end of an angular plate 15, which latter has its other end secured by screws or similar fastenings 16 to the inner side wall 17 of the adjacent section 2 of the track, as clearly shown in Fig. 4. It will be seen that when the sections 3 are swung inwardly to their folded positions, the spring loops 12 will be sprung over the heads or loops 14 and will be frictionally retained to retain said sections 3 in their dotted line position shown in Fig. 1.

Having thus described the invention what is claimed is:

1. A track for the casters of a bed or other piece of furniture comprising long and short channeled or trough-shaped sections, a hinge uniting the sections upon one side to permit them to fold against each other, a catch spring upon the other side of one of said sections, a pin upon the corresponding side of the other section adapted to be engaged by said catch spring to secure the sections in extended position, a keeper head upon the long section, and a spring loop upon the outer end of the short section and adapt-

ed to receive said head to retain the sections in folded position.

2. A track for the casters of a bed or other piece of furniture comprising channeled track sections, a hinge secured to one side of said sections to unite them for folding movement against each other, the spring catch member 10 formed from a strip of resilient material and bent at right angles and having one end secured to one side of one of the sections and its other end engaged with the end of such section and bent upon itself into U-form to provide a spring loop and the co-

acting catch member 15 consisting of a strap having one end secured to the side of the 15 other section and its other end bent at right angles and then upon itself to provide a head to enter said spring loop of the first mentioned catch member.

In testimony whereof I hereunto affix my 20 signature in the presence of two witnesses.

PHILIP RICHY CHABASSOL.
